PRESSURE GAGE FOR MEASURING FLUID
PRESSURES OR THE LIKE

Willard E. Buck, P.O. Box 357, Boulder, Colo.

Filed Apr. 13, 1959, Ser. No. 55,478

Term of patent 3½ years

(Cl. D52—6)

FIG. 1.

FIG. 2.

FIG. 3.

Figure 1 is a top plan view of the pressure gage for measuring fluid pressures or the like showing my new design;

Figure 2 is a front elevation thereof; and,

Figure 3 is a left side elevation thereof.

The undisclosed side of the pressure gage is the same in appearance as the side shown and the rear is substantially plain.

I claim:

The ornamental design for a pressure gage for measuring fluid pressures or the like, as shown and described.
